UNITED STATES PATENT OFFICE.

ADOLPH CHARLES VAN SLUYS, OF NASHUA, NEW HAMPSHIRE, ASSIGNEE TO NASHUA GUMMED AND COATED PAPER COMPANY, OF NASHUA, NEW HAMPSHIRE, A CORPORATION OF MASSACHUSETTS.

PACKAGING MACHINE.

Application filed May 28, 1921. Serial No. 473,295.

To all whom it may concern:

Be it known that I, ADOLPH CHARLES VAN SLUYS, a citizen of the United States, and a resident of Nashua, in the county of Hillsborough and State of New Hampshire, have invented an Improvement in Packaging Machines, of which the following description, in connection with the accompanying drawings, is a specification, like characters on the drawings representing like parts.

This invention relates to packaging machines, being more particularly concerned with the art of rolling sheets of waxed paper onto a core such as a cardboard tube and wrapping the same in a sheet of paper suitably fastened in place as by being crimped and tucked into the ends of the tube. The invention aims to provide a machine to perform the rolling and wrapping operations which heretofore have been performed by hand.

My invention will be best understood by reference to the following description when taken in connection with the accompanying drawings of one specific embodiment thereof, while its scope will be more particularly pointed out in the appended claims.

In the drawings:

Figs. 1^A and 1^B together constitute a side elevation of a packaging machine exemplifying my invention;

Fig. 2 is a side elevation similar to Fig. 1^A, but showing some of the working parts in another position;

Fig. 3 is a plan partly in section on line 3—3 of Fig. 2;

Fig. 4 is a plan partly in section on line 4—4 of Fig. 2, but showing some of the parts in another position;

Fig. 5 is a sectional view on line 5—5 of Fig. 3;

Fig. 6 is a sectional view on line 6—6 of Fig. 1^A; and

Figs. 7 to 10 inclusive illustrate various steps in the operation of crimping and tucking the wrapper into the ends of the tube.

Referring to the drawings and to the em-

bodiment of my invention which is illustrated therein, I have shown for purposes of exemplification a packaging machine in which a pile containing the desired number of sheets of waxed paper is received by a paper feeding mechanism which conveys the pile to a point where it is assembled with a suitable core such as a cardboard tube by a feeding mechanism which deposits the tubes one by one onto the respective piles of paper. Grippers of a winding mechanism then seize the sheets and tube and rotate the latter thereby winding the sheets thereonto. A sheet of wrapping paper is then brought into the path of the package and is wrapped about the latter by a wrapping mechanism which then crimps the ends of the wrapper and tucks them into the ends of the tube. The package when thus wrapped passes from the wrapping mechanism to a delivery mechanism which conveys the packages to a convenient point for removal by an operative. While the present embodiment of my invention requires the intervention of operatives, it should be understood that this is not at all essential, but is done for the sake of simplicity. These mechanisms will be described in the order in which they operate on a given package, followed by a description of the general operation of the machine as a whole.

I will first describe the waxed paper feeding mechanism, reference being had first to Figure 1^B. A pile of sheets of the paper, usually a dozen, is placed upon a set of conveyor belts 12 which connect pulleys 14 and 16 (the latter being best shown in Fig. 5) and extend across a platen 18. Lateral guides 20 spaced apart a proper distance for the width of the sheets guide the latter and insure a proper lateral registration. The conveyor belts carry the pile of sheets forward and bring them against a stop 22 (see the lower left hand part of Fig. 5) which brings the sheets to a state of rest and proper front registration.

The feeding mechanism for the cardboard tube will now be described, reference being had at first to Fig. 1^B. The tubes are placed in a chute 24 from which they gravitate onto a set of conveyor belts 26 connecting pulleys 28 and 30 (the latter being best shown in Fig. 5) and traveling across a platen 32. The conveyor belts advance a procession of the tubes with their peripheries in contact with one another to a downwardly inclined chute 34 down which they gravitate under the control of an escapement mechanism now to be described.

The escapement herein shown comprises a rocker 36 having two arms 38 and 40 which are alternately brought into the path of the tubes by a rocking motion. When the arm 38 is elevated, the arm 40 is depressed and serves as a stop to hold back the entire row of tubes by engagement with the foremost tube of the procession. When, however, the rocker is turned clockwise as viewed in Fig. 5, the arm 40 is elevated and the arm 38 is depressed. This action releases the foremost tube and permits the latter to gravitate down the chute, but the arm 38 prevents the next succeeding tube from following. When, therefore, the rocker is again turned in the reverse direction to its initial position the arm 40 is depressed into the path of the next tube and intercepts the latter when it is released by the elevation of the arm 38.

The escapement rocker is actuated by a suitable mechanism herein a rocking shaft 42 to which is secured an arm 44 connected by a pitman 46 to an eccentric strap 48 which encircles and is actuated by an eccentric 50, the latter being suitably secured as by a key 52 to a shaft 140. Rotation of this shaft therefore imparts a rocking motion to the escapement rocker and insures the delivery of the tubes one at a time onto the successive piles of paper brought to the assembling point by the paper feeding mechanism. In Fig. 5 a tube is shown resting upon pile of the sheets preparatory to the operation of winding the latter upon the tube.

The winding mechanism will now be described, reference being had to Figs. 4 and 6. The winding mechanism is in duplicate, there being one for each end of the tube,—hence it will be necessary to describe only one in detail. Adjacent to each end of the tube and axially aligned therewith at the point where the latter is deposited onto the pile of sheets is a suitable holder 56. In the present example the holder comprises a tapered plug 58 terminating in a cylindrical portion 60 whose diameter is such that it snugly fits the internal surface of the tube. The tapered portion insures easy entrance of the plug without danger of misalignment or lack of proper registration at the com-

mencement of its advance into the tube. The holder is herein provided with a shoulder 62 which brings up against the end of the tube and thus the latter is clamped endwise between the shoulders of the two holders. The holder is carried by suitable means herein a plunger 64 preferably a rotatable spindle mounted to turn in suitable bearings 66. A suitable plunger retracting compression spring 68 herein helically coiled about the plunger and bearing against abutments 70 and 72, one secured to the plunger, constantly tends to urge the latter in an outward direction,—that is to say out of engagement with the tube. A suitable latch, herein a lever 74 is adapted to enter a circumferential groove 76 in the plunger and to retain the latter in its inward position in opposition to the force exerted by the spring 68.

Inward movement of the plunger is herein effected by the use of a lever 78 fulcrumed at 80 and operated by a cam roll 82 cooperating with a cam 84 secured to a cam shaft 86. A suitable spring 88 maintains the cam roll in contact with the cam and restores the cam lever to its initial position after each inward movement of the plunger.

One convenient way of winding the paper on the tube is to rotate the latter while advancing it along and in contact with a suitable surface. To this end, each plunger is carried by a suitable carriage 90 of which the plunger bearings 66 in the present instance form a part (see Fig. 4). This carriage is guided by suitable guides 92, herein vertically arranged, that is to say perpendicularly to the path of feeding movement of the pile of sheets, before the latter is assembled with the tube. The carriage 105 is reciprocated on the guides by suitable mechanism presently to be described.

Since the sheets are to be wound upon a tube, there should be means provided to secure the forward edges of the sheets to the tube preparatory to and during the rotation of the tube, while the sheets are being wrapped about the latter. To this end, I have herein provided a gripper 94 associated with each holder 56, said gripper in the present example being in the form of a lever fulcrumed at 96 on a collar 98 fixedly secured to the plunger 64. This gripper is actuated by suitable means herein a link 100 pivoted at 102 to the gripper 94 and at 104 to a collar 106 mounted to slide axially on the plunger and normally held in a retracted position by a light spring 108, herein helically coiled about the plunger and resting at its opposite ends against the collars 98 and 106, respectively.

The relationship between the described pivotal connections is such that when the sliding collar 106 is thrust forward in opposition to the slight resistance presented 130

by the spring 108, the pivot 104 crosses a dead center, so to speak, by passing the pivot 102, thus preventing backward movement of the sliding collar and hence locking 5 the gripper 94 after the latter has been brought into gripping engagement with the sheets. Since the cylindrical portion 60 of the holder 56 snugly fits the interior of the tube, the latter cannot collapse and hence 10 the sheets are firmly gripped against the outer circumferential surface of the tube. It should be here understood that the spring 108 is so weak that it is insufficient at this time to move the collar 106 in an outward 15 direction. When, however, the proper moment arrives for the release of the grippers, this is effected by suitable means herein a stationary cam 110 against which the inner end of the sliding collar 106 is brought to: 20 ward the close of the upward travel of the carriage 90. By this means the pivot 104 connecting the sliding collar 106 and link 100 is moved in the other direction past the dead center presented by the pivot 102, and 25 the collar brings up against a suitable fixed stop 112, herein a collar secured to the plunger. The sliding collar is held in this position by the spring 108 and the gripper is held in its outward or retracted position 30 until such time as the collar is again thrust forward by suitable mechanism such as that now to be described.

Referring to Fig. 4, the collar 106 is advanced along the plunger 64 by a cam lever 35 114 fulcrumed at 116 and having a cam roll 118 cooperating with a cam 120 secured to the cam shaft 86 hereinbefore referred to. The cam is suitably shaped to cause the advance of the sliding collar and a consequent 40 gripping movement of the gripper 94 at the proper time in the operation of the machine,—that is to say at the moment after the tube has been deposited on the pile of sheets, as represented at the lower left hand part of 45 Figure 5. It should be understood, of course, that subsequently when the carriage commences its upward travel the collar 106 will move out of engagement with the cam lever 114 but that the collar will now be 50 held in its advanced position by the toggle-like effect of the link 100. It should also be understood that during the upward travel of the carriage the plunger will move out of registration with its actuating lever 55 78, but that the plunger will be held in its advanced position by the engagement of the latch 74 with the groove 76. When, however, the carriage reaches the proper point in its upward travel and after the release 60 of the gripper from the paper the holder 56 should be withdrawn from the tube. This is accomplished by the engagement of the latch 74 with a fixed stop 122 against which the latch is brought toward the close 65 of the upward movement of the carriage.

Vertical movement of each carriage is herein accomplished by the use of a pinion 124 meshing with a rack 126. The pinion 124 is suitably splined on the plunger 64 and thus rotates the latter while still allowing it to slide lengthwise, the pinion in the meantime being held against axial movement of the bearings 66 between which it is received, as best shown in Fig. 4. Assuming the rack to be held fixed and the carriage advanced lengthwise of the rack, naturally the pinion would rotate as a consequence of its advance along the rack and the plunger with its carrier and gripper would rotate and cause the winding of the paper on the tube during the upward travel of the carriage. This is the action which takes place during a part of the upward travel of the carriage, but the action is modified by stopping the rotation of the pinion at a certain point through the intervention of mechanism which causes the rack temporarily to advance with the carriage and at the same speed. This naturally stops the rotation of the pinion. 70 75 80 85 90

Reciprocation of the carriage is herein accomplished by the use of a lever 128 fulcrumed at 130 and provided with a forked end 132 in which is received a block 134 pivotally mounted on the plunger 64 (see Fig. 1). Upward and downward swinging movement of the lever is herein effected by a link 136 pivoted at one end to the lever and at its other end to a crank 138, the latter being secured to and driven by a shaft 140. Rotation of the latter is therefore accompanied by vertical reciprocation of the carriage 90. 95 100

In order that the rack may be held stationary at times and at other times allowed to travel vertically as previously explained, the rack is mounted to slide vertically in upper and lower guides 142 and 144 and there is provided a suitable spring-pressed 105 detent, herein a roller 146 carried by a lever 148 and arranged in rolling contact with one edge of the rack bar. The latter is provided with a depression 150 which the roller enters under the influence of a suitable spring 152. After the sheets have been wrapped about the tube, it is desirable that the rotation of the latter shall cease during the application of a sheet of wrapping paper as hereinafter explained. Previous to this, the rack bar is held against vertical movement by the engagement of the spring-pressed roller 146 with the depression 150, the degree of resistance being sufficient to enforce rotation of the pinion 124. When, however, it is desired that the rotation of 110 115 120 125 the pinion shall cease, the rack is advanced and the detent is thrown out by the mechanism which I will now describe.

A link 154 pivoted at 156 to the rack bar is provided with a slot 158 which re- 130

- ceives a pin 160 carried by the carriage reciprocating lever 128. The length and location of the slot with relation to the pin is such that during the first part of the 5 upward travel of the carriage the pin travels idly in the slot and hence causes no movement of the rack bar. During this period, the tube is rotated to wrap the sheets of paper thereon, by rolling the package 10 on a suitable platen herein a spring-pressed follower 162, pivoted at 164 and urged against the package by a spring 166, its movement being limited by a suitable fixed stop 168 (see Fig. 5). When, however, the pin brings up against the upper 15 end of the slot, the rack bar is caused to rise at a speed equal to that of the carriage. It follows that there is no relative movement of the rack and pinion,—hence the latter does not rotate and the holder 56 and gripper 94 are held against rotation during the application of a wrapper, as will now be explained.
- The wrapping mechanism will now be described, reference being had to Fig. 5. Arranged transversely of the path of the package is a platen 170, provided with lateral guides 172. A sheet of wrapping paper of the proper size is laid upon this platen between the guides and is advanced across an opening 174 provided in the platen until it brings up against a stop 176. Preferably the stop is so situated that the rear edge of the wrapping paper is somewhat farther 25 from the center of the tube than the forward edge. Above the opening 174 is a pair of vertical guides 178, whose lower edges are spaced from the upper surface of the platen a sufficient distance to allow the 30 wrapping paper to be introduced beneath the guides. The latter are spaced apart a distance slightly greater than the combined diameter of the tube and the sheets wound thereon. When, therefore, during the upward travel of the carriage, the package 35 brings up against the sheet of wrapping paper, the latter is removed from the platen and is wrapped part way around the package by being passed between the guides. This leaves the wrapper with two depending 40 marginal portions which must be brought together and lapped one over the other.
- The first step in this wrapping operation 45 is performed by one or more grippers 180, pivoted at 182 on a horizontally reciprocating carriage 184 carrying a pair of jaws 186 and 188 between which the package is received. A suitable spring 190 connected 50 to the gripper 180 constantly tends to carry the latter into gripping engagement with the package. Assuming the gripper to have been opened against the action of the spring by suitable mechanism presently to be described, the package is inserted between the 55 jaws 186 and 188 after which the gripper 180 closes on one flap of the wrapper and wraps the latter about the package, as shown in Fig. 5. The other flap is lapped over the first during and as a consequence 60 of the travel of the carriage from the position shown in full lines in Fig. 5 to the position shown in dotted lines therein in a manner now to be described.
- The carriage is mounted on suitable 65 guides herein a pair of rods 192 on which it is reciprocated by appropriate mechanism, herein a link 194 pivotally connected at one end to the carriage and at its other end to a lever 195 secured to a rock shaft 196 to 70 which is also secured a segmental gear 198 meshing with another segmental gear 200. The latter is mounted to rock on a stud 202 and is provided with an arm 204 carrying a pin 206 received in a slot 208 provided in a 75 link 210 pivoted at 212 to the lever 128 hereinbefore described. Rocking movement of the latter is therefore accompanied by reciprocating movement of the carriage on its guides, but owing to the provision of the 80 slot 208 the carriage has a period of rest at each end of its travel.
- The grippers 180 having closed upon one flap of the wrapper, as represented in full lines at the left-hand side of Fig. 5 85 should retain their grip thereon until after the completion of the wrapping operation and subsequently the grippers should open to release the completed package and should be in readiness for the reception of a second 90 package upon the return of the carriage toward the position shown in full lines in Fig. 5. To this end, I have herein provided suitable means consequent upon movement of the carriage toward the left in Fig. 5 to 95 cause the grippers to open, but on the other hand, to remain closed upon the package during the subsequent travel of the carriage toward the right. In the present example, each gripper carries a rocking lever 214, pivoted at 216 thereon, and having an arm 218 which is normally held in an upstanding position by a spring 222. Movement of the lever under the influence of the spring is limited by a suitable stop, herein a shoulder 224 presented by the upper end of the gripper 180. On the other hand, the rocking lever is free to be rocked in the opposite 100 direction in opposition to the spring by a plate 228 disposed in the path of the upper 105 end of the lever, as shown in Fig. 5. The length of the plate with respect to the travel of the carriage is such that when the latter moves toward the right the lever is rocked idly in one direction in opposition to the 110 spring as the lever passes beneath the plate, but on the other hand when the carriage travels toward the left from the position represented in dotted lines in Fig. 5, the upper 115 end of the rocking lever, after traveling a 120
- 125 130

- short distance, brings up against the right hand end of the plate and since the lever cannot rotate clockwise, owing to the provision of the stop 224, the lever and the gripper by which it is carried will be rocked as a unit about the fulcrum of the gripper. The gripper thus being opened, remains open until the rocking lever 218 clears the left-hand end of the plate 228, whereupon the gripper thus being released and allowed to swing under the influence of its spring 190 closes upon the package and wraps one flap of the wrapper about the package as shown in full lines at the left-hand side of Fig. 5.
- In order to enforce the period of rest provided for by the slot 208, I preferably provide suitable detent means herein comprising a disk 230 secured to the rock shaft 196 and provided with two depressions 232 and 234, either of which is adapted to receive a roller 236 carried by a lever 238 provided with a spring 240 which urges the roller into contact with the periphery of the disk. When the roller is held by the pressure of the spring in either depression, sufficient resistance is presented to prevent the shaft 196 from rocking until the pin 206 brings up against one end or the other of the slot 208 as the case may be, whereupon the roller rides out of the depression and the rock shaft turns, thereby imparting the desired movement to the carriage.
- During the travel of the carriage from the position represented in full lines in Fig. 5 toward the position shown in dotted lines therein, the second flap of the wrapper shown hanging straight downward at the left of Fig. 5 should be lapped over upon the first and held there until the ends of the wrapper have been crimped into the ends of the tube. One convenient way of accomplishing this is by simply providing a platen 242 arranged in the path of the pending flap and having a wiping action which wraps the same over and laps it upon the other edge of the wrapper. Preferably this platen is suitably mounted to yield radially with respect to the tube and herein is mounted upon a pivot 244 about which it is rocked and urged in an upward direction by a spring 246. A suitable stop 248 limits the upward movement under the influence of the spring. If desired, the forward or free edge of the platen may be bevelled or curved in a downward direction as at 250 to make sure that the package will ride up on the platen and depress the latter against the tension of the spring.
- Both margins of the wrapper now having been wrapped about the package and lapped one on the other and being firmly held in this position, the next step is to crimp the ends of the wrapper and tuck them into the ends of the tube. I will now describe

the crimping and tucking mechanism, reference being had to Fig. 3. The crimping and tucking is performed by a plurality of fingers 252 of any suitable number, herein four, fulcrumed on pivots 254 on a collar 256 fixedly secured to a plunger 258, the latter being mounted to slide horizontally in a guide 260. The plunger is reciprocated by a suitable mechanism, herein a lever 262 fulcrumed at 264 and connected by a link 266 to a lever 268, the latter being fulcrumed at 270 and carrying a cam roll 272 cooperating with a cam 274 secured to a cam shaft 276. A suitable spring 278, herein encircling the link 266, bears at one end 80 against a fixed abutment 280 and at its other end against an abutment 282 carried by the link, said spring serving to maintain engagement of the cam roll with the cam and to restore the plunger to its initial outward position after having been thrust inwardly by the action of the cam. Inward movement of the plunger is utilized for two purposes, first to cause the fingers to close upon and crimp the wrapper 90 inwardly, and second, to thrust the crimped wrapper into the ends of the tube. One convenient way of producing the closing and opening movement of the fingers is by utilizing the reciprocating movements of the plunger 258. To this end, I have herein provided a collar 284 mounted to slide lengthwise of the plunger 258 and connected to the fingers 252 by links 286, the arrangement being such that sliding movement of the collar is accompanied by opening or closing movement of the fingers according to the direction in which the collar is moved. A suitable spring 288, herein helically coiled about the plunger, is interposed between the fixed collar 256 and the sliding collar 284 and constantly tends to move the latter in a rearward or outward direction. In other words, the fingers are opened by the action of the spring.

The fingers are closed in opposition to the spring by a lever 290, one end of which is forked and provided with pins 292 received in a groove 294 provided in the sliding collar 284, while the other end carries a cam roll 296 cooperating with a fixed cam 298. The lever 290 is fulcrumed at 300 on a collar 302 secured to the plunger 258. It follows that reciprocating movement of the latter is accompanied by opening or closing movement of the fingers according to the direction in which the plunger is moved. The shape of the cam is such that the plunger at first travels inward without closing movement of the fingers. The latter, therefore, advance until they are inwardly beyond the end of the wrapper and adjacent the end of the tube. At this point, a step in the cam causes the sliding collar 284 to be advanced faster than the plunger 258,

thereby causing the fingers to be closed upon the wrapper and to crimp the same. The fingers continue to close until they are closed sufficiently to enter the tube, whereupon the closing movement ceases and continued forward movement of the plunger simply pushes the crimped edge of the paper into the interior of the tube. This having been done, the fingers recede and are restored to their initial position by a reversal of the foregoing movement.

The wrapping operation is now completed and nothing remains to be done but to discharge the finished package. The first step is to move the package from the position just described (in alignment with the plungers 258) to a point above an entrance 304 of a chute 306. This is accomplished during the travel of the horizontal carriage toward its initial position (toward the left Fig. 5). It will be remembered that during this movement of the carriage the grippers 180 are released from the package by the action of the fixed plate 228 on the rockers 218 carried by the grippers. This occurs when the package is immediately above the entrance 304 of the chute 306. It follows that the package is dropped into the chute and gravitates down the latter onto a set of feed belts 308 which connect pulleys 310 and 312 (see Fig. 1^B) and travel across a platen 314 (see Fig. 5). The chute is preferably provided with side walls or guides 316 which are prolonged along the sides of the platen 314 and thus guide the ends of the packages to a convenient point of delivery. In the present example, the packages bring up against a wall 318, at which point they may be removed by the hand of an operative. If desired, this wall might be omitted and the packages allowed to fall into a suitable receptacle.

The machine is provided with a suitable frame, herein comprising a pair of side frames 320 affording bearings for the several shafts and connected to each other by several cross ties which will now be described, reference being had first to Fig. 5. Two cross members 322 and 324 (see Fig. 1^B) connect the side frames and present supports for the platen 18 which it will be remembered supports the feed belts 12 of the mechanism which feeds the piles of waxed paper to the point of assembly with the tubes. A cross member 326 (see Fig. 5) also connects the side members and presents a convenient support for the stop 22 and the pivot 164 of the upright follower 162. The side frames 320 are further connected by cross members 328 and 330 which afford supports for the chute 24, platen 32 and the chute 34. Cross members 332 and 334 connect the side members and support the platen 170 with its guides 172 and stop 176, as well as the up-

right guides 178 and the cross member 334 further supports the chute 306. The side members are further connected by cross members 336 and 338 which support the guide rods 192 of the horizontally reciprocating carriage. The cross member 338 also supports the cam levers 268 of the crimping mechanism, as best shown in Fig. 3. A pair of cross members 340 also connecting the side members support the plate 228, which it will be remembered serves to open the grippers carried by the horizontally reciprocating carriage. The cam levers 78 which form a part of the winding mechanism and which are best shown in side elevation at the lower part of Fig. 1^A are supported by brackets 342. The cams 298 which form a part of the crimping and tucking mechanism are supported by brackets 344 secured to the side frames (see Fig. 1^A). The levers 262 which also constitute parts of the crimping and tucking mechanism are supported by brackets 346 secured to the side frames.

The machine is provided with a main driving pulley 348 secured to a shaft 350 journaled in suitable bearings in one of the side frames 320 and having also affixed to it a gear 352 meshing with a gear 354, the latter being secured to the shaft 140 which it will be remembered carries the cranks which impart a vertical reciprocatory motion to the vertical carriage. The shaft 140 drives the cam shaft 86 through a chain 356 and two sprocket wheels 358 and 360 secured to the respective shafts. The cam shaft 86 furnishes power to the feed belts 12 and to this end the pulleys 16 are secured to said shaft. The pulleys 14 which are driven by the feed belts are secured to a shaft 362 which is mounted in suitable bearings in the side frames and has secured to it a sprocket wheel 364 which is connected by a chain 366 with a sprocket wheel 368 (see Fig. 1^B), the latter being secured to a shaft 370 journaled in bearings in the side frames. The shaft 370 furnishes power to the feed belts 26 which it will be remembered feed the empty tubes, and to this end the pulleys 28 are secured to said shaft, while the pulleys 30 are secured to a shaft 372 (see Fig. 5) journaled in bearings on the cross member 328.

Also secured to the shaft 320 (see Fig. 1^B) is a gear 374 meshing with a gear 376, the latter being secured to a shaft 378 journaled in the bearings in the side frames and to this shaft are secured the pulleys 312 which drive the feed belts 308 which it will be remembered carry the complete packages to the point of discharge. The pulleys 310 are secured to a shaft 380 (see Fig. 5) which is journaled in bearings in the side frames.

The general operation should be clearly

understood from the foregoing description of the several mechanisms, but a brief résumé of the operation will now be given. An operative places successive piles *a* of the

- 6 waxed paper on the feed belts 12 and empty tubes *b* on the belts 26. The piles of paper and the tubes are fed to the assembling point (shown at the lower left-hand part of Fig. 5) where the tube is deposited on the pile of
- 10 sheets. The tube and sheets are then grasped by the cooperative action of the carriers 56 and grippers 94, whereupon the tube commences to rotate and wind the sheets thereon. An operative feeds wrappers *c* one at a time
- 15 at the proper instant into the path of the tube with the sheets wound thereon, and continued upward movement of the latter results in the wrapper being wrapped part way about the sheets as shown at the upper left-hand part of Fig. 5. The partially wrapped package is then carried in a horizontal direction toward the right as viewed in Fig. 5 into alignment with the crimping and tucking mechanism. Toward the close of this movement the edges of the wrapper are lapped one over the other and the wrapper is then in readiness to have its ends crimped and tucked, which operation now takes place
- 20 under the action of the crimping and tucking mechanism, and finally the completed package is deposited into the outlet chute and is carried away by the discharge feed belts to the point of delivery.

Having thus described one embodiment of my invention but without limiting myself thereto, what I claim and desire by Letters Patent to secure is:

Claims:

1. In a machine for making a package by assembling one or more sheets with a core, the combination of means to hold one or more sheets assembled with the core, and means to rotate said holding means about the axis of the core to wind the sheet or sheets onto the core.
2. In a machine for making a package by assembling one or more sheets with a core, the combination of means for grasping the sheet or sheets and core, and means about the axis of the core to rotate said grasping means to cause the sheet or sheets to be wound onto the core.
3. In a machine for winding one or more sheets onto a core, the combination of a platen, and sheet and core holding means, one mounted to yield relatively to the other in a direction generally normal to the work surface of said platen, and means to cause a relative motion of said platen and holding means in a direction generally parallel with said work surface, accompanied by rotation of said holding means.
4. In a packaging machine, the combination of means for applying a sheet and an outer wrapper to a core with the ends of the
- 5 wrapper projecting beyond the ends of the sheet and the core, and means for crimping the projecting ends of the wrapper.
5. In a packaging machine, the combination of means for holding a core by its ends, means for applying a wrapper to the core with the ends of the wrapper projecting beyond the ends of the core, means for holding the core and wrapper intermediate the ends, and means for collapsing the projecting ends of the wrapper. 70
6. In a packaging machine, the combination of means for applying a wrapper to a hollow core with the ends of the wrapper projecting beyond the ends of the core, and means for tucking the projecting ends of the wrapper into the ends of the hollow core. 80
7. In a packaging machine, the combination of means for holding a hollow core by engagement with the interior thereof, means for applying a wrapper to the core with the ends of the wrapper projecting beyond the ends of the core, means for holding the core and wrapper by engagement with the exterior thereof intermediate the ends, and means for collapsing the projecting ends of the wrapper. 85
8. In a packaging machine for combining sheets with cores to produce a succession of packages, the combination of means to feed a succession of cores, means to wind one or more sheets about each of a succession of cores, and means to apply a retaining element to said sheet or sheets to prevent the same from unwinding. 90 100
9. In a packaging machine for combining sheets with cores to produce a succession of packages, the combination of means to wind one or more sheets about each of a succession of cores, means to place a retaining element about said sheet or sheets and the enclosed core, and means to secure said retaining element in place about said sheet or sheets. 105
10. In a packaging machine for combining sheets with cores to produce a succession of packages, the combination of means for assembling each of a succession of cores with one or more sheets, and means for applying a wrapper to and about each core and the sheet or sheets assembled therewith. 110 115
11. In a packaging machine for combining sheets with cores to produce a succession of packages, the combination of means for assembling one or more sheets, with a core, means for applying a wrapper to and about said core and the sheet or sheets assembled therewith, and means to secure said wrapper in place about said sheet or sheets and said core. 120 125
12. In a packaging machine, the combination of means for assembling one or more sheets with a core, means for applying a wrapper thereto with the ends of the wrapper projecting beyond the ends of the core, 130

- and means for collapsing the projecting ends of the wrapper.
13. In a packaging machine, the combination of means for holding a core by its ends, means for assembling one or more sheets with said core while the latter is so held, means for applying a wrapper to said sheets and core while the latter is so held, means for holding said core, sheets and wrapper intermediate the ends thereof, and means for collapsing the projecting ends of the wrapper.
14. In a packaging machine for combining sheets with cores to produce a succession of packages, the combination of means for feeding sheets and cores to a place of assembly, means for winding the sheets about the cores and assembling them with wrappers, and means for applying the wrappers.
15. In a packaging machine for combining sheets with cores to produce a succession of packages, the combination of means for feeding sheets to a place of assembly, means for feeding cores toward the place of assembly and causing them to be deposited on the sheets, means for causing the winding of the sheets about the cores, and means for applying wrappers to the cores and the sheets thereon.
16. In a packaging machine for combining sheets with cores to produce a succession of packages, the combination of means for feeding sheets and cores to a place of assembly, means for winding the sheets about the cores, and assembling them with wrappers, means for applying the wrappers, and means for conveying the completed packages to a point of discharge.
17. In a packaging machine, the combination of means for holding a core by its ends, means cooperating with said core to grasp one or more sheets of paper, and means cooperating with said core to cause said sheet or sheets to be wound about said core.
18. In a packaging machine, the combination of means for holding a hollow core by entrance thereto, means cooperating therewith to grasp one or more sheets of paper, and means cooperating with said core to cause said sheet or sheets to be wound about said core.
19. In a machine for winding a sheet about a hollow core the combination of means to grasp said sheet and said core by engagement with the interior of said core, and means cooperating with said core to cause said sheet or sheets to be wound about said core.
20. In a machine for winding a sheet about a hollow core, the combination of two plugs adapted to enter the ends of said core, means to grasp said sheet, and means cooperating with said core to cause said sheet to be wound about said core.
21. In a machine for winding a sheet about a hollow core, the combination of means to support the core, grippers to grip the sheet against the core, and means cooperating with said core to cause said sheet to be wound about said core.
22. In a machine for winding a sheet about a hollow core, the combination of means to support the core, grippers to grip the sheet against the core, and means to wrap the sheets about the core by rotating the core and said grippers.
23. In a machine for winding a sheet about a hollow core, the combination of core-supporting means, sheet-grasping means, and means to utilize movement of said core-supporting means into and out of said core, to operate said sheet-grasping means.
24. In a machine for winding a sheet about a hollow core, the combination of axially movable, rotatable, core-supporting means, radially movable, sheet-grasping means carried by said core-supporting means, and means to cause axial movement of said core-supporting means to accompany radial movement of said sheet-grasping means.
25. In a machine for winding a sheet about a hollow core, the combination of tapered, axially movable, core-supporting means, means to cause said core-supporting means to enter the core, sheet-grasping means, and means to rotate said sheet-grasping means to cause the sheet to be wrapped about the core.
26. In a machine for winding a sheet about a hollow core, the combination of core-supporting means comprising two plugs adapted to enter opposite ends of the core, sheet-grasping means carried by said sheet-supporting means, and core-rotating means.
27. In a machine for winding a sheet about a hollow core, the combination of core-supporting means comprising two plungers adapted to enter opposite ends of the core, means to move said plungers into and out of the core, sheet-grasping means, and means to rotate said sheet-grasping means about an axis within said core.
28. In a machine for winding a sheet about a core, the combination of core-supporting means, sheet-grasping means, wiping means, and means to cause relative rotation of said sheet-grasping means and said wiping means about an axis within said core, to wrap said sheet about said core.
29. In a machine for winding a sheet about a core, the combination of core-supporting means, sheet-grasping means, an arc-shaped member adapted to confine the sheet about the core, and means to rotate said sheet-grasping means about an axis within said core to cause the sheet to be wrapped about the core.
30. In a machine for winding a sheet about a core, the combination of core sup-

porting means, sheet-grasping means, an arc-shaped member adapted to confine the sheet about the core, and means to cause relative movement of said core and said

5 member to wrap said sheet about said core.

31. In a machine for winding a sheet about a core, the combination of core-sup-

porting means, sheet-grasping means, a platen, and means to cause a relative movement between the core and said platen to 10 wrap the sheet about the core.

In testimony whereof, I have signed my name to this specification.

ADOLPH CHARLES VAN SLUYS.

porting means, sheet-grasping means, an arc-shaped member adapted to confine the sheet about the core, and means to cause relative movement of said core and said member to wrap said sheet about said core.

31. In a machine for winding a sheet about a core, the combination of core-sup-

porting means, sheet-grasping means, a platen, and means to cause a relative movement between the core and said platen to wrap the sheet about the core.

In testimony whereof, I have signed my name to this specification.

ADOLPH CHARLES VAN SLUYS.

Certificate of Correction.

It is hereby certified that in Letters Patent No. 1,542,781, granted June 16, 1925, upon the application of Adolph Charles van Sluys, of Nashua, New Hampshire, for an improvement in "Packaging Machines," an error appears in the printed specification requiring correction as follows: Page 7, lines 49 and 50, claim 2, strike out the words "about the axis of the core" and insert the same to follow after the word "means", line 50; and that the said Letters Patent should be read with this correction therein that the same may conform to the record of the case in the Patent Office.

Signed and sealed this 14th day of July, A. D. 1925.

[SEAL.]

WM. A. KINNAN,
Acting Commissioner of Patents.
